NURSING NIPPLE FOR USE WITH A NURSING BOTTLE

Michael C. Ritsi, 7950 SW. 16th St.,
Miami, Fla. 33155

Filed Aug. 29, 1968, Ser. No. 13,312

Term of patent 14 years

Int. Cl. D24—05

U.S. Cl. D83—8

Fig. 1

Fig. 2

Fig. 3

Fig. 4

FIG. 1 is a perspective view of a nursing nipple for use with a nursing bottle showing my new design;

FIG. 2 is a front elevational view;

FIG. 3 is a top plan view; and

FIG. 4 is a bottom plan view thereof.

I claim:

The ornamental design for a nursing nipple for use with a nursing bottle, as shown and described.
